CLAIM

I claim the ornamental design for the sanitizing wipe container, as shown and described.

DESCRIPTION

FIG. 1 is a front view of the sanitizing wipe container.

FIG. 2 is a rear view of the claimed design.

FIG. 3 is a left side view of the claimed design.

FIG. 4 is a top view of the claimed design.

FIG. 5 is a bottom view of the claimed design; and,

FIG. 6 is a perspective view of the claimed design.

The toilet and wall lines of FIG. 6 are in broken lines, and is environmental matter forming no part of the claimed design.
